STERLING TURNER, OF SALEM, MASSACHUSETTS, ASSIGNOR TO HYGRADE LAMP CO.,
OF SALEM, MASSACHUSETTS, A CORPORATION OF MASSACHUSETTS.

INCANDESCENT LAMP.

Application filed February 18, 1928. Serial No. 255,277.

This invention relates to incandescent electric lamps and more especially to gas filled lamps of this character.

In using incandescent lamps filled with nitrogen, argon, or other gas, especially where such lamps are connected in series as, for example, on street railway circuits, it is a common experience for an arc to form in a lamp due to the breaking of a filament. Such an arc may create sufficient heat to cause the lamp to explode, or the arc may follow up the leading-in wires, burn out the base, and even burn into the socket and fixture in which the lamp is supported. It has been proposed heretofore to prevent destructive arcing of this character by enclosing the leading-in wires in glass tubes, the tubes being so supported that they will be released automatically upon the formation of an arc and will then drop and tend to cut off the arc. It has been found, however, that such an arrangement cannot be depended upon. In some cases a tube will be released by the arc in the manner contemplated and the arc then will flash across to the part of the leading-in wire above the tube. In other cases the tube will stick and the arc will cut its way through a tube, following up the leading-in wire with the same ultimate result as though the tube were not present. While it has been proposed to prevent the latter occurrence by using tubes of fused quartz, this involves a relatively large increase in the expense of manufacture of the lamp.

The present invention deals with the problem presented by these conditions, and it aims to devise a lamp construction in which an arc created in the manner above described will be automatically extinguished, and to accomplish this result with a construction in which the manufacturing expense will be held within reasonable limits.

The nature of the invention will be readily understood from the following description when read in connection with the accompanying drawings, and the novel features will be particularly pointed out in the appended claims.

In the drawings,

Figure 1 is a perspective view of a lamp constructed in accordance with this invention, certain of the parts being shown broken away;

Fig. 2 is a view similar to Fig. 1 but showing the position of the parts when one of

the insulating tubes has been released by the formation of an arc; and

Fig. 3 is a cross-sectional view, partly in elevation, showing certain details of construction on a larger scale.

The lamp structure shown comprises a glass envelope or bulb 2 equipped with the usual base 3 and stem 4. The glass bulb preferably is filled with a gas such as argon, nitrogen, or the like. Projecting downward from the press portion of the stem is a pedestal 5 having a series of wires sealed into the lower extremity thereof for supporting or steadyng the filament 6. Current is conducted to the filament by leading-in wires 7-7', respectively. The arrangement so far described is substantially like that of lamps of well known constructions.

According to the present invention the leading-in wires 7-7' are enclosed in and protected by insulating tubes 8-8', respectively, these tubes extending from the press of the stem 4 down nearly to the end of each leading-in wire. The tubes are held permanently on the leading-in wires in any suitable manner, as for example, by bending the leading-in wires at intermediate portions, as clearly shown in the drawings, so that each tube will be held frictionally on its respective wire. Slidably mounted on the tubes 8-8' are insulating sleeves 9-9', respectively. In order to hold the sleeve 9 in its elevated position, as shown in Fig. 1, a small wire 10 is sealed in the lower end of the pedestal 5, while its other end is wrapped around the lower portion of the leading-in wire 7, the lower edge of the tube 9 resting on this wire, as clearly shown in Fig. 1. A similar construction is used to support the other tube 9', and the parts used for this purpose are shown on a larger scale in Fig. 3. These wires 10-10' may be made of any material which will support the sleeves in their elevated positions during shipment and normal operation of the lamp, but which will melt out readily and release the tubes upon the formation of an arc between the lower ends of the leading-in wires. I have obtained very satisfactory results by using nickel wire of approximately twenty-thousandths of an inch in diameter.

Normally the sleeves 9-9' are held in their elevated inactive positions, as shown in Fig. 1, the wires 10-10' having ample strength for this purpose. When an arc occurs between 110

the leading-in wires it quickly fuses one or both of the meltable wires 10—10', thus releasing at least one of the sleeves 9 or 9'. The sleeve so released immediately drops until its lower end strikes the inner surface of the globe 2, and it therefore cuts off and extinguishes the arc. The sleeves 9—9' slide freely on the tubes 8—8', respectively, and any possibility of the sticking of the sleeves is avoided.

10 At the same time the sleeve and tube for each leading-in wire are made of such length that when the sleeve has dropped, as shown for example in Fig. 2, the entire length of the leading-in wire is enclosed in the insulating members and there is no opportunity for the arc to strike back to an exposed portion of the wire.

The tubes 8—8' and the sleeves 9—9' may be made of any suitable insulating material.

20 I have obtained very satisfactory results by making the tubes 8—8' of common glass and the sleeves 9—9' of a more refractory or higher melting point glass, such for example, as that known commercially as Pyrex glass. It is contemplated, however, that these parts, and particularly the sleeves, may be made of other insulating material, such for example, as mica, or a material known as "isolantite".

The construction above described has proved in practice to be extremely reliable and the manufacturing expense is within entirely satisfactory limits.

While I have herein shown and described a preferred embodiment of my invention, it will be understood that the invention may be embodied in other forms without departing from the spirit or scope thereof.

Having thus described my invention, what I desire to claim as new is:

40 1. In an incandescent electric lamp, the combination of a filament, leading-in wires for said filament, a protector for one of said wires, and an insulating sleeve slidable on said protector.

45 2. In an incandescent electric lamp, the combination of a filament, leading-in wires for said filament, a protector for one of said wires, an insulating sleeve slidable on said protector, and means for holding said sleeve normally in an inactive position but adapted to release the sleeve upon the formation of an arc between said wires.

3. In an incandescent electric lamp, the combination of a filament, leading-in wires for said filament, an insulating tube enclosing one of said wires, and an insulating sleeve loosely encircling said tube and slidably mounted thereon, said tube and sleeve serving to protect said wire and to extinguish an arc between said wire.

60 4. In an incandescent electric lamp, the combination of a filament, leading-in wires

for said filament, an insulating tube through which one of said wires extends for a considerable distance, said tube fitting closely 65 around said wire, an insulating sleeve loosely encircling said tube and slidably thereon, and means for holding said sleeve normally in an inactive position but adapted to release the sleeve automatically upon the formation of 70 an arc between said wires.

5. In an incandescent electric lamp, the combination of a filament, leading-in wires for said filament, a pedestal for supporting said filament, an insulating sleeve through 75 which said wire extends for a considerable distance, said sleeve being slidable relatively to said wire, and means connected with said pedestal for releasably holding said sleeve normally in an inactive position, said means being adapted to release said sleeve upon the formation of an arc between said wires.

6. In an incandescent electric lamp, the combination of a filament, leading-in wires for said filament, a pedestal for supporting 85 said filament, an insulating sleeve through which said wire extends for a considerable distance, said sleeve being slidable relatively to said wire, and means connecting the wire so enclosed with said pedestal for releasably 90 holding said sleeve normally in inactive position, said means being adapted to release said sleeve upon the formation of an arc between said wires.

7. In an incandescent electric lamp, the combination of a filament, leading-in wires for said filament, a pedestal for supporting said filament, an insulating tube enclosing one of said wires and permanently held thereon, a sleeve of refractory insulating material encircling said tube and slidably thereon, and a meltable wire connecting said pedestal with the leading-in wire enclosed in said tube and supporting said sleeve in position to be released upon the fusing of said meltable wire 105 by an arc.

8. In an incandescent electric lamp, the combination of a filament, leading-in wires for said filament, a glass envelope in which said filament and leading-in wires are mounted, an insulating tube enclosing one of said wires within the envelope, an insulating sleeve loosely enclosing said tube and slidably mounted thereon, and means for releasably holding said sleeve in an elevated position but adapted to release the sleeve upon the formation of an arc between said wires to permit said sleeve to drop and cut off the arc, said sleeve and tube being of such lengths as to protect the entire length of the leading-in 110 wire when the sleeve has dropped to the lower limit of its movement.
